AIR EXPANSION POWER SYSTEM

Frederick Nettel, Manhasset, and Johann
Kreitner, New York, N. Y.

Application July 10, 1941, Serial No. 401,703

9 Claims. (Cl. 60—59)

The present art of expansion power systems uses open cycles with heating of the working medium by internal combustion of fuel in it, or closed cycles with heating through heating surfaces.

Closed cycles can utilize any type of fuel, but they are suffering from many defects which impeded their practical use.

The broad object of this invention is to avoid these defects, simplify the arrangement and to improve the efficiency.

It is a further specific object of this invention to provide a power system for double fuel operation.

The broad object is achieved by burning the fuel in a portion of the expanded air branched off after passing through part or the whole of the heat exchanger and by leading the gases and the exhaust air in separate streams through said heat exchanger and thence to the atmosphere.

Pure air only is working in the expansion machine. The temperature limit for the heated air is mostly dictated by the blading material of the turbine, and the surface heaters are designed for said limiting temperature. There are, however, other cases, where the metallurgical properties of the tube material of said heaters restrict the air temperature at the heater outlet to lower values than the turbine blading can stand. Since the overall thermal efficiency of air expansion power plants rises sharply with increasing turbine inlet temperature, this invention includes a combination of indirect heating as described hereinbefore, with additional direct heating by internal combustion. According to this invention, the bulk of the heat input is supplied by burning cheap fuel, for example coal, in air discharged from the turbine, and the combustion heat transferred through heating surfaces to the compressed air, which is thus heated up to the metallurgical limit for the heater tubes. Thereafter a comparatively small quantity of fuel suitable for internal combustion, namely one which burns practically free from ash, residue or other deleterious concomitants, is injected into the hot compressed air and burned therein, whereby the air is heated further, up to the temperature permissible for the turbine blading. Such double fuel operation may be continuous or only temporary, such as for instance in power plants where base load is produced by burning cheap fuel, and peak load by additional internal combustion of gaseous or liquid fuel in an internal combustion chamber disposed in front of the turbine inlet.

In the drawings affixed to this specification and forming part thereof, several embodiments of this

invention are illustrated diagrammatically by way of non-limiting examples as follows:

Fig. 1 represents an air turbine power plant for electric power generation for the utilization of pulverized coal or lowest grade liquid fuel.

Fig. 2 shows an alternative embodiment involving reheating of the air for utilization of solid fuel on a travelling grate.

Fig. 3 represents an alternative embodiment of the regenerative heat exchanger.

Fig. 4 shows a modification of Fig. 2 with subdivided combustion chamber served by two travelling grates and an induced draft fan for the gases discharged from the heat exchanger.

Fig. 5 represents a modification of Fig. 1 with the furnace air branched off behind the regenerative heat exchanger and fed back into the air pipe from the turbine before said heat exchanger, and an additional internal combustion chamber for burning liquid fuel during double fuel operation.

The plant according to Fig. 1 operates as follows: Air is taken in at 1 into the first stage compressor 2, cooled in the intercooler 3, compressed further in the second stage compressor 4, from which it flows into the tube system of the regenerative heat exchanger 5, in which it is preheated as will be explained hereafter. From 5 it flows through pipe 6 and through the heating coil 7, which latter is arranged within the combustion chamber 8, and through pipe 9 to the air turbine 10, where it expands to a pressure near the atmospheric pressure while developing mechanical power to drive the compressors 2 and 4 and the electric generator 11, which latter supplies useful power. The expanded, but still very hot air leaves turbine 10 at 12 and flows partly through the heat exchanger 5 where it is used to preheat the compressed air before being discharged to the atmosphere at 13. Another part of the hot air discharged from the turbine flows via a regulating flap 14 and duct 15 to the combustion chamber 8 where it is used in the burner 16, supplied with pulverized coal from source 17, to heat the compressed air flowing through the heating coil 7 disposed within said combustion chamber. The combustion gases formed in chamber 8 leave the latter at 18 to flow through the regenerative heat exchanger 5, where they also heat the compressed air within the tube system before being expelled to the atmosphere at 19. Cooling water for the intercooler enters at 20 and is discharged at 21. From air duct 15 a branch duct 22 leads directly into 8 with flap valve 23 arranged at the branching point. Fuel valve 24, which opens when

turned anti-clockwise, is coupled by linkage as shown to thermostat 25 with elastic bellows 26 and to flyball governor 27. The latter is driven from turbine shaft.

Load and temperature regulation is effected as follows: With increasing load the governor sleeve 29 moves downwards while point 30, which is connected to the thermostat bellows, remains stationary during the first moments. Thus point 28 also moves downwards with the result that fuel valve 24 opens and flap 23 admits more air to the burner. The increased heating causes the temperature at 25 to rise and the bellows to expand, moving point 30 downwards. Finally the system finds a new position of equilibrium geometrically coordinating more fuel to a higher temperature in pipe 9 and to a slightly lower rotative speed. At reduction of load the reverse action takes place. Apart from the ordinary load regulation the described arrangement at the same time acts as safety device against excess speed and excess air temperature in coil 7.

While for pulverized coal firing highly pre-heated combustion air is very advantageous, the temperature of such air for grates is limited by design reasons to about 200 deg. C. For such plants the method of air supply is modified as will be shown in Fig. 2.

The power plant as per Figure 2 operates as follows: Air is taken in from the atmosphere at 31, compressed in first stage compressor 32, inter-cooled in cooler 33, which is shown in the example as of the water spray type in which cold water is sprayed in counterflow to the compressed air as indicated in Fig. 1 in more detail. The air is further compressed in second stage compressor 34, flowing hereafter through the tube system of the regenerative heat exchanger 35, thence through pipe 36 into the heating coil 37, arranged within the combustion chamber 38, and through pipe 39 into the first stage air turbine 40 which drives the electric generator 41. From turbine 40 the air flows in a partly expanded condition through a second heating coil 37', also disposed within said combustion chamber 38, in which the air is reheated, flowing hereafter through the second stage turbine 40' in which it expands to a pressure near the atmospheric pressure while delivering mechanical power to drive part compressors 32 and 34, and is finally expelled in part at 43 into the ambient atmosphere. The remainder of that air is, however, branched off behind the heat exchanger via flap valve 44 into duct 45, which leads it under the travelling grate 46 disposed in combustion chamber 38, thus supplying warm air for the combustion of the coal which is fed to said travelling grate from coal chute 47. The combustion gases formed in 38 leave it at 48 to flow also through the regenerative heat exchanger 35, in which they also preheat the compressed air coming from compressor 34, to be hereafter expelled to the atmosphere at 49. For load regulation it may be desirable to regulate the heating of the air in coils 37 and 37' independently. In such cases it is advantageous to provide separate grate, stokers or for pulverized coal firing separate burners, for each of the heating coils.

The principal difference between the arrangements shown in Fig. 1 and Fig. 2, as regards the surface heaters, consists in the combustion air being branched off before the regenerative heat exchanger 5 in Fig. 1 and after the heat exchanger 35 in Fig. 2.

In some cases it is desired to supply the air 75

for the combustion chamber at a temperature below that at which it is discharged from the turbine but higher than that at which it leaves the heat exchanger. For this purpose the re-

5 generative heat exchanger is modified as shown in Fig. 3. The air discharged from the air turbine enters at 60, flows as indicated by dotted line up to the outlet branch 61 provided with a flap valve 62. At this point part of the air is 10 branched off to the combustion chamber (not shown) while the remaining portion flows on through the whole length of the heat exchanger, leaving it at 63. The combustion gases from the 15 combustion chamber enter at 64 and flow as also indicated by dotted line, through the whole length of the heat exchanger, leaving it at 65.

The plant as per Fig. 4 operates generally in the same manner as that of Fig. 2. The combustion chamber, however, is sub-divided by a 20 wall 38' into two part-chambers in communicating connection at the top. Each part-chamber is served by its own travelling grate 46' and 46" to which air is fed through pipes 45' and 45" respectively. The two grates permit to 25 control the heating in the coils 37 and 37' individually. To control the flow of the combustion gases through the part-chambers and through the heat exchanger 35, an induced draft fan 49' is disposed in the outlet pipe 49 from said heat 30 exchanger.

The plant as per Fig. 5 operates in principle in the same manner as that shown in Fig. 1. However, the air for the combustion chamber 8 is branched off behind the heat exchanger 5, 35 through pipe 15', fan 15'', pipes 22 and the coal burner 16 into the combustion chamber 8. The gases leave this chamber by pipe 18' and are led into the pipe coming from the air turbine 10, 40 where they mix with the air discharged from said turbine. The branched-off air is not quite pure, containing a very small quantity of combustion products, which, however, have no effects on the combustion in chamber 8. Another special feature of this example of the invention consists in the provision of the internal combustion chamber 52, disposed in pipe 9, in which additional liquid fuel is burned to heat the working air to a higher temperature than is done in heater coil 7. This liquid fuel is fed to chamber 52 from 45 fuel tank 56 via fuel pump 55, pipe 54 with regulating valve 53. Thus part of the heat required in the system is produced by pulverized coal in an external furnace, and another part by liquid fuel in an internal combustion chamber.

55 It is immaterial to this invention what types of turbines, expansion engines, compressors, coolers, regenerative heat exchangers and combustion devices are used and what kind of fuel is burned in the latter.

60 Manifestly, variations may be resorted to, equivalents of parts introduced, and parts may be used without others within the broad scope of the invention and its features.

Having now described our invention, we claim:

65 1. In the method of producing power by successively compressing, heating and expanding a gaseous working fluid, the combination of compressing an air stream, preheating it by surface heat transfer from said same stream after its expansion, heating it further by surface heat transfer from the gaseous products of an external fuel combustion effected at substantially atmospheric pressure, heating it still further by internal combustion of fuel in said compressed air, expanding the resulting compressed and

heated air-gas mixture to substantially atmospheric pressure, thereby developing power, cooling said air-gas mixture by said surface heat transfer to said compressed air, ejecting a portion of said expanded and cooled air-gas mixture to the atmosphere, utilizing the remaining portion of said expanded and cooled air-gas mixture as combustion supporting medium for said external combustion, cooling the resultant combustion gases by said surface heat transfer to said compressed air, and ejecting said cooled combustion gases to the atmosphere.

2. In a power system including means to take in a continuous stream of air from the ambient atmosphere, means to compress it, regenerative heat exchange means to preheat it after compression, surface type fuel burning means to heat it further, an expansion machine disposed to develop power by expansion of said compressed and heated air, conduit means connecting in succession, the outlet of said compressing means to the inlet of the heated side of said heat exchange means, the outlet of the latter to the inlet of said fuel burning heating means, the outlet of the latter to the inlet of said expansion machine, the outlet of the latter to the inlet of the heating side of said heat exchange means, the outlet of the latter to the atmosphere, conduit means for branching off a portion of the expanded air after it has passed through said regenerative heat exchange means, and for leading it to said fuel burning heating means so as to use said branched off air as combustion air, said heating means being designed for air inlet temperatures under 200 deg. C.

3. In a power system including means to take in a continuous stream of air from the ambient atmosphere, means to compress it in stage compressors with interposed cooling means, regenerative heat exchange means to preheat said air after compression, surface type fuel burning means to heat it further, an expansion machine disposed to develop useful power by partial expansion of said compressed and heated air, second surface type fuel burning means to reheat the air issuing from said expansion machine, a second expansion machine disposed to develop power for driving said compressors by expansion of the partially expanded reheated air to near-atmospheric pressure, conduit means for connecting in succession, the outlet of the highest pressure stage compressor to the inlet of the heated side of said heat exchange means, the outlet of the latter to the inlet of said first surface type fuel burning heating means, the outlet of the latter to the inlet of said first expansion machine, the outlet of the latter to the inlet of said second surface type fuel burning reheating means, the outlet of the latter to the inlet of said second expansion machine, the outlet of the latter to the inlet of the heating side of said heat exchange means, the outlet of the latter to the atmosphere, conduit means for branching off a portion of the expanded air after it has passed through said regenerative heat exchange means, and for leading it to both said fuel burning heating means so as to use said branched off air as combustion air, said fuel burning heating means being designed for air inlet temperatures under 200 deg. C.

4. In a power system according to claim 3, first and second surface type fuel burning heating and reheating means for the air being independent of each other as regards adjustment of fuel feed.

5. In a power system including means to take in a continuous stream of air from the ambient atmosphere, means to compress it, regenerative heat exchange means to preheat it after compression, surface type fuel burning heating means to heat it further, an expansion machine disposed to develop power by expansion of said compressed and heated air, conduit means for connecting in succession, the outlet of said compressing means to the inlet to the heated side of said heat exchange means, the outlet of the latter to the inlet of said fuel burning heating means, the outlet of the latter to the inlet of said expansion machine, the outlet of the latter to the inlet of the heating side of said heat exchange means, the outlet of the latter to the atmosphere, conduit means for branching off a portion of the expanded air after it has passed through said regenerative heat exchange means, and for leading it to said fuel burning means so as to use said branched off air as combustion air, conduit means for leading the products of combustion from said fuel burning heater to the heating side of said regenerative heat exchange means, and flow dividing means in said regenerative heat exchange means to allow the air issuing from said expansion machine and the products of combustion from the fuel burning heater to flow in separate substantially parallel streams through the heating side of said regenerative heat exchange means.

6. In a power system including means to take in a continuous stream of air from the ambient atmosphere, means comprising stage compressors with interposed cooling means to compress the air, regenerative heat exchange means to preheat said air after compression, surface type fuel burning means to heat it further, an expansion machine disposed to develop useful power by partial expansion of said compressed and heated air, second surface type fuel burning means to reheat said air issuing from said expansion machine, a second expansion machine disposed to develop power for driving said compressors by expansion of the partially expanded reheated air to near-atmospheric pressure, conduit means for connecting in succession, the outlet of the highest pressure stage compressor to the inlet of the heated side of said heat exchange means, the outlet of the latter to the inlet of said first fuel burning heating means, the outlet of the latter to the inlet of said first expansion machine, the outlet of the latter to the inlet of said second fuel burning reheating means, the outlet of the latter to the inlet of said second expansion machine, the outlet of the latter to the inlet of the heating side of said heat exchange means, the outlet of the latter to the atmosphere, conduit means for branching off a portion of the expanded air after it has passed through said regenerative heat exchange means, and for leading it to both said fuel burning heating and reheating means so as to use said branched off air as combustion air, conduit means for leading the products of combustion in said fuel burning heaters to the heating side of said regenerative heat exchange means, and flow dividing means in said regenerative heat exchange means to allow the air issuing from said second expansion machine and the products of combustion from the fuel burning heaters to flow in separate substantially parallel streams through the heating side of said regenerative heat exchange means.

7. In a power system according to claim 6, first and second surface type fuel burning heat-

ing and reheating means for the air being independent of each other as regards adjustment of fuel feed.

8. In a power system including means to take in a continuous stream of air from the ambient atmosphere, means to compress it, regenerative heat exchange means to preheat it after compression, surface type fuel burning means to heat it further, an expansion machine disposed to develop power by expansion of said compressed and heated air, conduit means for connecting in succession, the outlet of said compressing means to the heated side of said heat exchange means, the outlet of the latter to the inlet of said fuel burning heating means, the outlet of the latter to the inlet of said expansion machine, the outlet of the latter to the inlet of the heating side of said heat exchange means, the outlet of the latter to the atmosphere, conduit means for branching off a portion of the expanded air after it has passed through said regenerative heat exchange means, and for leading it to said fuel burning heating means so as to use said branched off air as combustion air, and conduit means for leading the products of combustion from said fuel burning heater into the heating side of said re-

generative heat exchange means, so as to admix them to the air issuing from said expansion machine.

9. In the method of producing power by successively compressing, heating and expanding a gaseous working fluid, the combination of compressing an air stream, preheating it by surface heat transfer from said same stream after its expansion, heating it further by surface heat transfer from the gaseous products of an external fuel combustion effected at substantially atmospheric pressure, expanding the compressed and heated air to substantially atmospheric pressure thereby developing power, cooling said expanded air by said surface heat transfer to said compressed air stream, ejecting a portion of said expanded and cooled air to the atmosphere, utilizing the remaining portion of said expanded and cooled air as combustion air for said external combustion, cooling the resultant combustion gases by said surface heat transfer to said compressed air stream, and ejecting said cooled combustion gases to the atmosphere.
